UNITED STATES PATENT OFFICE.

JOHN J. GAYNOR, OF INDIANAPOLIS, INDIANA.

BOTTLE-LABELING MACHINE.

1,197,476.

Specification of Letters Patent. Patented Sept. 5, 1916.

Application filed March 13, 1916. Serial No. 83,983.

To all whom it may concern:

Be it known that I, JOHN J. GAYNOR, a citizen of the United States, residing at Indianapolis, in the county of Marion and State of Indiana, have invented certain new and useful Improvements in Bottle-Labeling Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to bottle labeling machines and has for its object to provide improvements in machines of this class in the following particulars: First: In the construction and arrangement of the parts so that the bottles to be labeled are conveyed to the labeling machine in a horizontal position and are delivered from the labeling mechanism in an upstanding position. Second: In the construction and arrangement of the label carriers whereby the rotating carriers move to and from the label box or boxes in a straight line, thereby assuring a proper picking of the labels from the box or boxes. Third: In the mechanism for increasing the speed of the label carrier with relation to the label affixing finger at the instant that the label is being stripped from the label carrier, so that a more perfect and uniform positioning of the label on the bottle is assured. Fourth: In the production of a machine for labeling bottles at a high rate of speed, and in accomplishing this in a simple, cheap and effective manner. Fifth: In eliminating complicated mechanisms which are easily deranged and in the construction which permits of the label box being maintained normally stationary and at a point above the labeling mechanism so as to protect the labels from damage.

The invention consists in the construction and arrangement of the parts for accomplishing the aforementioned objects, and the invention further consists in certain combinations of parts, all of which will be first fully described and afterward specifically pointed out in the appended claims.

Referring to the accompanying drawings: Figure 1 is a plan view of a labeling machine constructed in accordance with this invention, the label box being removed to better illustrate the parts. Fig. 2 is a rear

elevation. Fig. 3 is a vertical longitudinal sectional view. Fig. 3^a is a diagrammatic view of the label carrier. Fig. 4 is a side elevation illustrating the gearing mechanism. Fig. 5 is a diagrammatic view illustrating the positions of the several sets of labeling mechanisms and particularly a pair of labels being stripped from one of the label carriers and applied to a bottle. Fig. 6 is a similar view illustrating a bottle with labels thereon being passed through the label wipers. Fig. 7 is a diagrammatic view illustrating the positions of a pair of the labeling devices, the label carrier being illustrated as about to approach the label box to pick a label or labels therefrom. Fig. 8 is a similar view illustrating a label carrier in the position of picking a label or labels from the label box. Fig. 9 is a similar view illustrating a label carrier with label thereon moving away from the label box. Fig. 10 is a similar view illustrating a label carrier about to be influenced by the cam to be turned thereby into position to have its label or labels picked therefrom. Fig. 11 is a similar view illustrating one of the label carriers under the influence of the cam and turned into position to meet its label stripping fingers. Fig. 12 is a similar view illustrating one of the label carriers about to have its label picked therefrom and in the act of being swung from its first position into its second position, during which swing its speed with relation to its label picking finger is increased. Fig. 13 is a similar view illustrating one of the label carriers at the completion of its swing from second to first position and illustrating one of the bottle carriers and bottle under full influence of its rail, and also illustrating the labels picked from the label carrier and applied to the bottle. Fig. 14 is a similar view illustrating one of the label carriers in position of receiving paste from the paste roll and also illustrating the labeled bottle after having passed through the label wipers. Fig. 15 is a fragmentary elevation of the label box in its abnormal or raised position. Fig. 16 is a fragmentary view partly in elevation and partly in section of one of the label carriers and its immediate connections. Fig. 17 is an elevation of the four label carriers showing their bifurcated positioning arms. Fig. 18 illustrates in side and in edge elevation one of the bottle carriers and its immediate connections, and Fig. 19 is an elevation illus-

trating the four bottle carriers and particularly their controlling and positioning mechanism.

Like numerals of reference indicate the 5 same parts throughout the several figures.

It is thought that a brief description of the general operation of the machine will be helpful as a means to a better and a more thorough understanding of the mechanisms 10 which will be hereinafter specifically described in connection with the accompanying drawings.

The labeling machine forming the subject of this present invention, comprises an endless conveyer having bottle receiving devices thereon upon which bottles are manually placed to be conveyed to the labeling mechanism. In the labeling of certain classes of bottles which are invariably provided with 15 names or trade-marks blown in the bottles and forming protuberances thereon it is quite necessary that the label or labels be applied to the smooth surfaces of the bottles and not directly upon the lettered or 20 marked portions thereof, as obviously labels so applied on the lettered or marked portions of a bottle would not only cover up that which is intended to be visible but at the same time would prevent the smooth 25 and effective application of the label or labels thereon. The arrangement of the horizontally positioned endless conveyer provides for the proper positioning of the bottles thereon so that they will be delivered 30 to the labeling mechanism to receive their labels upon the smooth surfaces thereon and not on the lettered or marked portions thereof.

The machine includes in association with 40 the endless conveyer a plurality of bottle holding devices movably mounted on a disk rotating on a horizontal axis and a plurality of label stripping fingers mounted on said rotatable disk and stationary relative 45 thereto, the said bottle holders being so arranged and positioned as to receive successively bottles from the endless conveyer.

The machine further includes a plurality of label carriers movably mounted on a disk 50 rotating on a horizontal axis and having in co-action therewith certain mechanical devices for moving and positioning the label carriers so that upon rotation of their mounting disk said label carriers will first 55 receive a suitable quantity of paste from a paste roll, then pick a label or labels from a label box or boxes and finally meet the label stripping finger to have its label or labels stripped therefrom and applied to a 60 bottle.

The machine also includes a suitable label wiping device arranged stationary through 65 which the bottles with labels thereon are successively passed so as to wipe and smooth out the label or labels, and the machine

finally includes a hopper and an endless conveyer into which hopper and upon which conveyer the labeled bottles are dropped from the label carriers in an upright or upstanding position to be delivered from 70 the machine.

With the foregoing brief outline of the operation of the machine, reference is made to the accompanying drawings and to the numerals of reference thereon in which:

1 indicates the bottle labeling machine which includes the suitable frame 2, and 3 indicates the horizontally positioned endless conveyer passing over suitable sprocket wheels 4 at the front end of the machine 80 and over the driving sprocket wheels 5 which sprocket wheels 5 are mounted on a driving shaft 6 to one end of which is secured a sprocket wheel 7 chained to a sprocket wheel 8 on the central shaft 9 by 85 means of which and other intergeared mechanism the endless conveyer 3 is driven, this said conveyer 3 is provided with a plurality of transverse blocks 10 having their edges chamfered at 11 and properly spaced apart 90 so as to provide pockets or recesses for the reception of bottles to be conveyed to the labeling mechanism, it being understood that suitable sprocket chains 12 support the 95 said blocks 10.

Referring now to the bottle holding mechanism and particularly to Figs. 3, 5, 6, 18 and 19 it will be seen that the same includes a disk 13 mounted on the rotatable shaft 9 and rotatable therewith on a horizontal axis 100 and it will be seen from said figures that a plurality of bottle carriers 14 are pivoted at 15 equidistant from one another on the inner face of the said disk 13, each of said bottle carriers 14 including a curved bottle body conforming recess 16 and a horizontally projecting arm 17 (Fig. 18) at the end of which is provided a curved bottle neck receiving member 18 so that a bottle is supported and carried in this holder in the manner as shown in dotted lines in Fig. 18. In this connection and referring particularly to Figs. 3, 18 and 19 it will be seen that there are pivoted on the outer face of the disk 13 at the points 19 a plurality of levers 20 each having a roller 21 on its outer end, a bifurcated portion 22 on its inner end and it will be seen that the said disk 13 is provided with a series of slots 23 through which a pin 24 on each of the bottle carriers 14 extends and enters the bifurcated portion 22 of the lever 20. An inspection of the before mentioned figures of the drawings will show that the bottle carriers 14 will be swung on their pivots 15 by 110 the levers 20 acting on the pins 24 on said bottle carriers and in order to swing said bottle carriers 14 into position to receive the bottles from the endless conveyer 3, I provide above the rotatable disk 13 an 115 120 125 130

arced rail 25 (Figs. 3 and 19) which is arranged in the path of movement of the rollers 21 on the levers 20 so that upon rotation of the disk 13, the rollers 21 will successively engage the said rail 25 and cause the bottle carriers 14 to swing on their pivots 15 as shown in Fig. 6 to receive bottles from the endless conveyer and to cause same to approach the label stripping fingers 26 mounted stationary on the said disk 13, it being understood that this swinging movement of the bottle carriers 14 is accomplished in connection with the label carriers which will be hereinafter described so that when a label is stripped from one of the label carriers by one of the label stripping fingers 26, its associated bottle carrier 14 with its bottle therein will be swung on its pivot 15 under the influence of its lever 20 and the rail 25 to bring the bottle into engagement with the label or labels which have been stripped from the label carrier by the label stripping finger.

While describing the bottle carrying devices and its associated mechanism it is well to refer to Figs. 5 and 6 which illustrate the position of the label wipers 27 which as shown in said figures are positioned in the path of movement of the bottles in the bottle carriers so as to wipe and smooth out the label or labels while the bottle carriers are still under the influence of the rail 25. When however the rollers 21 or the levers 20 pass beyond the rail 25 each bottle carrier 14 engages an obstacle 28 disposed in its path of movement in the manner as shown in Fig. 6 which causes the bottle carriers 14 to be swung on their pivots 15 away from the label stripping finger 26, thus successively releasing the labeled bottles and causing them to drop successively into the hopper 29 arranged above the delivery conveyer 30, the said hopper being so constructed and positioned that the necks of the bottles are delivered in a recess 31 in the side 32 of the hopper 29, thus causing the bottles to be tripped and delivered on the conveyer 30 in an upright position as shown in Fig. 2.

Referring now to the label carriers and their associated mechanisms reference is made particularly to Figs. 3, 16 and 17 and to the diagrammatic views 7, 8, 9, 10, 11, 12, 13 and 14. The label carriers 33 are bifurcated as shown and include two flat portions 34 and 35 to receive either a single body label or a body label and a neck label. Each of said label carriers 33 is journaled in a member 36 which is itself pivoted at 37 on the outer face of the horizontally rotating disk 38 which is mounted on and rotatable with the shaft 39 upon which shaft is mounted a spur gear wheel 40 meshing with a spur gear wheel 41 on the shaft 9 which mounts the bottle carrying devices

just described, said spur gear wheels being of a ratio of 1 to 1, the said shafts 9 and 39 and the said disks 13 and 38 being rotated in opposite directions synchronously. Referring again to Fig. 16 it will be seen that each of the label carriers 33 is provided with a crank 42 upon the pin of which is mounted a roller 43. It will thus be seen that a compound swinging movement can be imparted to the label carriers 33 inasmuch as each label carrier can be swung on its journal in the member 36 under influence of its crank and roller 42 and 43 while a swinging movement can be imparted to the label carrier 33 and to its journaling member 36 by swinging said journaling member on its pivot 37. This compound swinging movement of the label carriers 33 is a material feature of this invention as by such movement I am enabled to more perfectly pick a label or labels from the label box or boxes and to effect a more perfect stripping of the label or labels from the label carriers by the label stripping fingers as well. For this reason I will lay particular stress upon this compound swinging action of the label carriers and their associated mechanisms for effecting the same.

Arranged stationary and adjacent the rotating disk 38 as shown in Fig. 3, is a cam 44 disposed in the path of movement of the rollers 43 on the crank 42 of the label carriers 33 by means of which the said label carriers 33 are swung on their journals in the members 36 as from the position shown in Fig. 10 into position shown in Fig. 11 in order to reverse the position of the label carriers with labels thereon just previous to the stripping of the labels therefrom and to maintain the label carriers in proper position during the stripping operation as when passing from position shown in Fig. 12 into position shown in Fig. 13.

The normal position of the label carriers 33 is tangential to the disk 38 as shown in Figs. 8, 10 and 14, and this tangential position is maintained by means of a guide member 45 (Figs. 16 and 17) connected at the journal of each label carrier 33 and extending substantially radially of the disk 38 and straddling the shaft 39. The bifurcated end 46 of each of said guide members 45, allows a radially sliding action and at the same time assures a proper tangential position of the label carriers as when in the position for picking a label as shown in Fig. 8. The normal tangential position of the label carriers 33 is assured by means of a small stop 47 (Figs. 16 and 17) on the outer end of each guide member 45 which extends over the label carrier 33, against which stop each label carrier 33 is held by a suitable coil spring 48 connected to diametrically opposite label carriers 33.

Referring now to Figs. 3 and 3^a which show the disk 38 in elevation opposite to that of Fig. 17, it will be seen that each opposite pair of pivoted label carrier journaling members 36 which are each pivoted to the disk 38 at 37 are connected together by links 49 pivoted thereto to one side of the pivotal points 37 of the said carrier journaling members 36, so that swinging movement of one of the said pivoted members 36 will be communicated to the opposite pivoted member 36. The purposes of this construction and movement will be presently described.

Arranged in rear of the machine, and adjacent the labeling devices is the paste-box 50 in which is horizontally mounted the paste feed roller 51 on a shaft 52 driven by a pulley 53 belted to a pulley 54 mounted on a shaft 55 carrying the main driving drum or pulley 56. Pivoted at 57 on an arm 58 is the paste distributing roller 59 normally in rolling contact with the rotating paste feed roller 51. Connected to said arm 58 and extending forwardly and substantially horizontally is an elongated arm 60 disposed in the path of movement of the pins 61 (Fig. 2) horizontally mounted on the rotatable disk 62 carried on the rotating shaft 39, (diagrammatically illustrated in Figs. 5 and 6), said pins 61 on the disk 62 being so positioned as to successively engage the forwardly extending arm 60 to bring the paste distributing roller 59 from position shown in Fig. 5 into position shown in Fig. 6 to be engaged by a label carrier 33 so as to distribute paste on the label carrying surfaces 34 and 35 thereof.

Arranged uppermost of the machine is the label box or boxes 63 for supporting the labels 64 in stationary position to be picked successively by the label carriers 33. Said label box or boxes are pivoted to an arm 65 at 66 which extends forwardly of the machine and is pivoted in an upright 67 at 68, said arm 65 having a vertical extension 69 pivoted to a rack bar 70 whose teeth 71 are held into engagement with a pin 72 on the upright 67 by means of a spring 73. The label box or boxes 63 is or are also pivoted at 74 to a bracket 75 mounted on the frame of the machine. By means of this construction, the label box or boxes 63 can be manually raised into position shown in Fig. 15 and out of reach of the label carriers 33 to prevent, should occasion require, the picking of a label or labels by the label carrier or carriers 33.

Referring now particularly to Figs. 3, 7, 8, 9 and 16 it will be seen that each of the journals of the label carriers 33 is provided with a reduced outer end 76 extending horizontally beyond the normal surface of the crank arms 42, thereby forming substantially transversely projecting pins, and it

will be seen that there is provided adjacent the label box or boxes 63 a stop 77 arranged in the path of movement of the projecting pins 76. It will further be seen that the periphery of the disk 38 is provided on each side of the pivotal point 37 of each of the label carrier journaling members 36 with depressions 78 and 79, the latter depression being deeper than the former, both depressions being so positioned that the shallower depression will receive the barrel 80 of the pivoted label carrier journaling member 36 when the same is in its first position as shown in Fig. 7, while the deeper depression 79 will receive the same when in its second position as shown in Fig. 9. The said projecting pin 76 and the pivoted label carrier journaling member 36 and label carrier 33 always meet the stop 77 when the pivoted label carrier journaling member 36 is in its first position as shown in Fig. 7, and as said stop 77 is in the path of rotation of the pin 76, rotation of said pin is stopped. As soon however as the pin 76 strikes the stop 77, the gravity actuated pivoted dog 78', drops over the pin 76 as shown in Fig. 3 thus securely holding said pin in engagement with the face of the stop 77. While the stop 77 holds the pin 76 against rotary movement, the disk 38 continues to rotate thus causing the pivotal label carrier journaling member 36 to swing on its pivot 37. This causes the label carrier 33 to move directly upward in a straight line into position shown in Fig. 8 and pick a label or labels 64 from the label box or boxes 63, and as the swing of the pivoted label carrier journaling member 36 is completed, the label carrier 33 recedes from the label box 63 downwardly in a straight line and assumes its second position as shown in Fig. 9. As the recess or seat 79 in the periphery of the disk 38 is deeper than the recess or seat 78 therein, the projecting pin 76 following the swing of the pivoted member 36 and its increased depression by reason of its deeper recess or seat 79, is carried down below and out of engagement with the stop 77 as shown in Fig. 9, so that the label carrier 33 with its label or labels thereon is now free to rotate with the disk 38.

As each of the pivoted label carrier journaling members 36 is connected by a link 49 to the opposite pivoted member 36 as shown in Figs. 3 and 3^a, the swing of one of said members 36 under the influence of the stop 77 from its first position shown in Fig. 7 to its second position shown in Fig. 9, causes its diametrically opposite pivoted member 36 to be swung from its second position shown in Fig. 11 through position shown in Fig. 12 into its first position shown in Fig. 13. This swing of the diametrically opposite pivoted member 36 occurs while its journaled label carrier 33 is under the

influence of the cam 44, and the swing of said latter member 36 and its label carrier 33 is in the direction of rotation of the disk 38 as will be seen from Fig. 3^a in which dotted lines indicate the position at the end of the swing. The movement imparted to the label carrier 33 by reason of the swing of its pivoted journaling member 36 in the direction of rotation of the disk 38 when added to the normal rotary movement of said disk, causes a greatly increased speed to the label carrier 33 at the interval of the said swing, which greatly increased speed occurs at the instant the label stripping finger is stripping the label from the said label carrier as will be hereinafter fully described.

Having thus described the several parts of the machine and the several movements of the several parts thereof, its operation is as follows: The bottles to be labeled are placed manually upon the endless conveyer 3 to be conveyed to the bottle carriers 14 as heretofore described. We will consider the application of paste to one of the label carriers 33 as shown in Fig. 14 as the first operation. The paste distributing roller is brought out into engagement with the faces of the label carriers 33 to distribute paste thereon through the medium of the mechanism heretofore set forth. From the paste roller, the label carrier progresses in rotary movement into position shown in Fig. 7, whereby reason of the projecting pin 76 and the stop 77, the label carrier 33 with paste thereon is moved upwardly in a straight line against the lowermost label or labels 64 in the label boxes 63 as shown in Figs. 3 and 8, and said label carrier with label or labels thereon returns in a straight line into its second position shown in Fig. 9, the pivoted label carrier journaling member 36 having completed its swing and positioning the projecting pin 76 so as to clear the stop 77 to allow the label carrier to again take up the rotation of the disk 38. The label carrier 33 progresses by rotary movement into position shown in Fig. 10 in which position the roller 43 on the label carrier crank engages the cam 44. Further progression of the label carrier 33 with its disk 38 causes the label carrier under the influence of the cam 44 to be swung on its journal from its normal tangential position shown in Fig. 10 into substantially a reverse position as shown in Fig. 11, with its label or labels facing in the direction of rotation of the disk 38. As the label carrier 33 reaches this position, its fellow or mating bottle carrier 14 also reaches the position shown in Fig. 11 and is about to receive its bottle. As the label carrier reaches the position shown in Fig. 12, its pivoted journaling member 36 has commenced its swing in the direction of rotation of the disk 38, un-

der the influence of the swing of the diametrically opposite pivoted member 36 which is now passing from position shown in Fig. 7 to position shown in Fig. 8. The speed of the label carrier 33 shown in Fig. 12 is now increased and it is rapidly approaching and overtaking the label stripping finger 26 rotating with the bottle carrier disk 13. The roller 21 on the bottle carrier positioning lever 20 is about to be influenced by the rail 25. As the bottle carrier 33 completes its swing it overtakes and passes beyond the label stripping finger 26 into position shown in Fig. 13 said finger passing completely through the bifurcated label carrier 33 and stripping its label or labels therefrom. Simultaneously the roller 21 on the bottle carrier positioning lever 20 becomes influenced by the rail 25 and swings the bottle carrier 14 on its pivot 85 15 into position shown in Fig. 13 and in engagement with the label or labels 64 on the label stripping finger 26 which labels have been just stripped from the label carrier 33. Further progression of the label carrier 33 carries the roller 43 out of engagement with the cam 44, and the spring 48 (Fig. 17) swings the label carrier into its normal tangential position to again receive paste from the paste roller as shown in Fig. 95 14. While the label carrier 33 is progressing into this latter position, the bottle with label or labels thereon is being passed through the label wipers 27 and as the label carrier 33 passes from position shown in Fig. 14 into position shown in Fig. 7, the roller 21 on the bottle carrier positioning lever 20 passes off of its rail 25 (Fig. 6) and the bottle carrier 14 engages the obstacle 28 in its path of rotation which swings the bottle carrier on its pivot 15 away from its label stripping finger, thus releasing the bottle and depositing the same within the hopper 29, by which it is tripped as previously described and is delivered onto the 100 conveyer 30 in an upright or upstanding position as shown in Fig. 2.

Having thus fully described the invention and its operation, the foregoing specification when taken in connection with the accompanying drawings will be perfectly clear to those skilled in the art, and while I have shown and described what I consider the preferable embodiment, I do not wish to be understood as limiting myself to the exact 115 or similar constructions, but I consider myself clearly entitled to any and all changes and modifications as fall within the limit and scope of the appended claims.

What I claim as new and desire to secure 125 by Letters Patent of the United States is:

1. An article labeling machine including article labeling devices rotatable on a horizontal axis, means for rotating said labeling devices, a label box arranged above said 130

labeling devices and normally stationary relative thereto, said rotatable labeling devices including means for moving the same to and from said label box in a vertical line during continuous rotation of said rotating means.

2. An article labeling machine including article labeling devices rotatable on a horizontal axis, means for rotating said labeling devices, a label box arranged above said labeling devices and normally stationary relative thereto, said rotatable labeling devices including means for moving the same to and from said label box in a straight line, during continuous rotation of said rotating means.

3. An article labeling machine including rotatable article labeling devices, means for rotating the same, a label box in association therewith and means for moving the rotatable labeling devices in the direction of the label box in a straight line to pick labels therefrom and to move the rotatable labeling devices with labels thereon away from the label box in a straight line during continuous rotation of said rotating means.

4. An article labeling machine including rotatable article labeling devices, means for rotating the same and a label box normally stationary relative thereto, and means for moving said rotatable labeling devices to and from said label box in a vertical line during continuous rotation of said rotating means.

5. An article labeling machine including rotatable article labeling devices, means for rotating the same and a label box normally stationary relative thereto, and means for moving said rotatable labeling devices to and from said label box in a straight line during continuous rotation of said rotating means.

6. An article labeling machine including a relatively stationary label box, rotatable labeling mechanism associated therewith, means for rotating the same and means co-acting with said rotatable labeling mechanism for moving the same to and from said label box in a vertical line during continuous rotation of said rotating means.

7. An article labeling machine including a relatively stationary label box, rotatable labeling mechanism associated therewith, means for rotating the same and means co-acting with said rotatable labeling mechanism for moving the same to and from said label box in a straight line during continuous rotation of said rotating means.

8. An article labeling machine including a relatively stationary label box, rotatable labeling mechanism associated therewith and means for changing the rotary movement of said labeling mechanism into a vertical reciprocating movement to pick labels from said label box.

9. An article labeling machine including a relatively stationary label box, rotatable labeling mechanism associated therewith, and means for changing the rotary movement of said labeling mechanism into a straight reciprocating movement to pick labels from said label box.

10. An article labeling machine including a relatively stationary label box, rotatable labeling mechanism, means for changing the rotary movement of said labeling mechanism into straight reciprocating movement to pick labels from the label box, and means for moving the label box out of the path of movement of said labeling mechanism.

11. An article labeling machine including means for holding labels, labeling mechanism including rotatable label carriers, means for rotating the same and means for changing the rotary movement of said label carriers to a straight line movement to pick labels from said label holding means during continuous rotation of said rotating means.

12. An article labeling machine including article labeling devices which include label carriers rotatable on a horizontal axis, means for rotating the same, a label box arranged above said labeling devices and normally stationary relative thereto, and means for moving the rotatable label carriers to and from said label box in a vertical line during continuous rotation of said rotating means.

13. An article labeling machine including article labeling devices which include label carriers rotatable on a horizontal axis, means for rotating the same, a label box arranged above said labeling devices and normally stationary relative thereto, and means for moving the rotatable label carriers to and from said label box in a straight line during continuous rotation of said rotating means.

14. An article labeling machine including article labeling devices which include rotatable label carriers, means for rotating the same, a label box in association therewith and means for moving the rotatable label carriers in the direction of the label box in a straight line to pick labels therefrom and to move the rotatable label carriers with labels thereon away from the label box in a straight line during continuous rotation of said rotating means.

15. An article labeling machine including rotatable article labeling devices which include rotatable label carriers, means for rotating said devices and label carriers, a label box, and means for moving said rotatable label carriers to and from said label box in a vertical line during continuous rotation of said rotating means.

16. An article labeling machine including rotatable article labeling devices which include rotatable label carriers, means for ro-

- 5 tating said devices and label carriers, a label box, and means for moving said rotatable label carriers to and from said label box in a straight line during continuous rotation of said rotary means.
- 10 6 17. An article labeling machine including a label box, labeling mechanism including rotatable label carriers, means for rotating the same, and means coacting with said rotatable label carriers for moving the same to and from said label box in a vertical line during continuous rotation of said rotating means.
- 15 18. An article labeling machine including a label box, labeling mechanism including rotatable label carriers, means for rotating the same, and means coacting with said rotatable label carriers for moving the same to and from said label box in a straight line during continuous rotation of said rotating means.
- 20 19. An article labeling machine including a label box, labeling mechanism including rotatable label carriers, and means for changing the rotary movement of said label carriers into a vertical reciprocating movement to pick labels from said label box.
- 25 20. An article labeling machine including a label box, labeling mechanism including rotatable label carriers, and means for changing the rotary movement of said label carriers into a straight reciprocating movement to pick labels from said label box.
- 30 21. An article labeling machine including a label box, labeling mechanism including rotatable label carriers, means for changing the rotary movement of said label carriers into straight reciprocating movement to pick labels from the label box, and means for moving the label box out of the path of movement of said label carriers.
- 35 22. An article labeling machine including article labeling devices which include label carriers rotatable on a horizontal axis, means for rotating the same, a label box in association therewith, and means for moving the rotatable label carriers in the direction of the label box in a straight line to pick labels therefrom and to move the rotatable label carriers with labels thereon away from the label box in a straight line during continuous rotation of said rotating means.
- 40 23. An article labeling machine including rotatable article labeling devices which include label carriers rotatable on a horizontal axis, means for rotating the same, a label box, and means for moving said rotatable label carriers to and from said label box in a vertical line during continuous rotation of said rotating means.
- 45 24. An article labeling machine including rotatable article labeling devices which include label carriers rotatable on a horizontal axis, means for rotating the same, a label box, and means for moving said rotatable
- 50 label carriers to and from said label box in a straight line during continuous rotation of said rotating means.
- 55 25. An article labeling machine including a label box, labeling mechanism including label carriers rotatable on a horizontal axis, means for rotating the same, and means coacting with said rotatable label carriers for moving the same to and from said label box in a vertical line during continuous rotation of said rotating means. 70
- 60 26. An article labeling machine including a label box, labeling mechanism including label carriers rotatable on a horizontal axis, means for rotating the same, and means coacting with said rotatable label carriers for moving the same to and from said label box in a straight line during continuous rotation of said rotating means. 75
- 65 27. An article labeling machine including a label box, labeling mechanism including label carriers rotatable on a horizontal axis and means for changing the rotary movement of said label carriers into a vertical reciprocating movement to pick labels from said label box. 80
- 70 28. An article labeling machine including a label box, labeling mechanism including label carriers rotatable on a horizontal axis and means for changing the rotary movement of said label carriers into a straight reciprocating movement to pick labels from said label box. 85
- 75 29. An article labeling machine including a label box, labeling mechanism including label carriers rotatable on a horizontal axis, means for changing the rotary movement of said label carriers into straight reciprocating movement to pick labels from the label box and means for moving the label box out of the path of movement of said label carriers. 90
- 80 30. A bottle or like labeling machine including rotatable bottle or like labeling devices, a label box in association therewith, means for moving the rotatable labeling devices in the direction of the label box in a straight line to pick labels therefrom and to move the rotatable labeling devices with labels thereon away from the label box in a straight line and to carry same to bottles or the like to be labeled, and means for stripping the labels from the rotatable label carriers and affixing same to bottles or the like. 95
- 85 31. A bottle or like labeling machine including rotatable bottle or like labeling devices, a label box, means for moving said rotatable labeling devices to and from said label box in a vertical line to pick labels therefrom and means for stripping the labels from said labeling devices and affixing same to bottles or the like. 100
- 90 32. A bottle or like labeling machine including rotatable bottle or like labeling de- 105
- 95 110
- 100 115
- 105 120
- 110 125
- 115 130

5 vices, a label box, means for moving said rotatable labeling devices to and from said label box in a straight line to pick labels therefrom and means for stripping the labels from said labeling devices and affixing same to bottles or the like.

10 33. A bottle or like labeling machine including a label box, rotatable labeling mechanism, means coacting with said rotatable labeling mechanism for moving the same to and from said label box in a vertical line, to pick labels therefrom and means for stripping the labels from the labeling mechanism and affixing same to bottles or the like.

15 34. A bottle or like labeling machine including a label box, rotatable labeling mechanism, means coacting with said rotatable labeling mechanism for moving the same to and from said label box in a straight line, to pick labels therefrom and means for stripping the labels from the labeling mechanism and affixing same to bottles or the like.

20 35. A bottle or like labeling machine including a label box, rotatable labeling devices, means for changing the rotary movement of said labeling devices into a vertical reciprocating movement to pick labels from said label box and means for stripping the labels from said labeling devices and affixing same to bottles or the like.

25 36. A bottle or like labeling machine including a label box, rotatable labeling devices, means for changing the rotary movement of said labeling devices into a straight reciprocating movement to pick labels from said label box and means for stripping the labels from said labeling devices and affixing same to bottles or the like.

30 37. A bottle or like labeling machine including a label box, rotatable labeling devices, means for changing the rotary movement of said labeling devices into straight movement to pick labels from the label box, means for moving the label box out of the path of movement of the labeling devices, and means for stripping the labels from the labeling devices and affixing same to bottles or the like.

35 38. A bottle or like labeling machine including means for holding labels, label mechanism including rotatable label carriers, means for changing the rotary movement of said label carriers to a straight line movement to pick labels from said label holding means, said labeling mechanism also including means for stripping the labels from said carriers and affixing same to bottles or the like.

40 39. A bottle or like labeling machine including labeling devices which include label carriers rotatable on a horizontal axis, a label box arranged above said labeling devices and normally stationary relative thereto, means for moving the rotatable label car-

riers to and from said label box in vertical line, said labeling devices also including means for stripping the labels from said carriers and affixing same to bottles or the like.

45 40. A bottle or like labeling machine including labeling devices which include label carriers rotatable on a horizontal axis, a label box arranged above said labeling devices and normally stationary relative thereto, means for moving the rotatable label carriers to and from said label box in a straight line, said labeling devices also including means for stripping the labels from said carriers and affixing same to bottles or the like.

50 41. A bottle or like labeling machine including labeling devices which include rotatable label carriers, a label box, means for moving the rotatable label carriers in the direction of the label box in a straight line to pick labels therefrom and to move the rotatable label carriers with labels thereon away from the label box in a straight line, said labeling devices including means for stripping the label from the carriers and affixing same to bottles and the like.

55 42. A bottle or like labeling machine including rotatable labeling devices which include rotatable label carriers, a label box, means for moving said rotatable label carriers to and from said label box in a vertical line to pick labels therefrom, said rotatable labeling devices also including means for stripping the labels from the rotatable label carriers and affixing same to bottles or the like.

60 43. A bottle or like labeling machine including rotatable labeling devices which include rotatable label carriers, a label box, means for moving said rotatable label carriers to and from said label box in a straight line to pick labels therefrom said rotatable labeling devices also including means for stripping the labels from the rotatable label carriers and affixing same to bottles or the like.

65 44. A bottle or like labeling machine including a label box, labeling mechanism including rotatable label carriers, means coacting with said rotatable label carriers for moving the same to and from said label box in a vertical line to pick labels therefrom, said labeling mechanism also including means for stripping the labels from the label carriers and affixing same to bottles or the like.

70 45. A bottle or like labeling machine including a label box, labeling mechanism including rotatable label carriers, means coacting with said rotatable label carriers for moving the same to and from said label box in a straight line to pick labels therefrom, said labeling mechanism also including means for stripping the labels from the label carriers and affixing same to bottles or the like.

46. A bottle or like labeling machine including a label box, labeling mechanism including rotatable label carriers, means for changing the rotary movement of said label carriers into a vertical reciprocating movement to pick labels from said label box, said labeling mechanism also including means for stripping the labels from the label carriers and affixing same to bottles or the like.
- 5 47. A bottle or like labeling machine including a label box, labeling mechanism including rotatable label carriers, means for changing the rotary movement of said label carriers into a straight reciprocating movement to pick labels from said label box, said labeling mechanism also including means for stripping the labels from the label carriers and affixing same to bottles or the like.
- 10 48. A bottle or like labeling machine including a label box, labeling mechanism including rotatable label carriers, means for changing the rotary movement of said label carriers into straight reciprocating movement to pick labels from the label box and means for moving the label box out of the path of movement of said label carriers, said labeling mechanism also including means for stripping the labels from the label carriers and affixing same to bottles or the like.
- 15 49. A bottle or labeling machine including labeling devices which include label carriers rotatable on a horizontal axis, a label box, means for moving the rotatable carriers in the direction of the label box in a straight line to pick labels therefrom and to move the rotatable label carriers with labels thereon away from the label box in a straight line, said labeling devices including means for stripping the labels from the label carriers and affixing same to bottles or the like.
- 20 50. A bottle or like labeling machine including rotatable labeling devices which include label carriers rotatable on a horizontal axis, a label box, means for moving said rotatable label carriers to and from said label box in a vertical line to pick labels therefrom, said labeling devices including means for stripping the labels from the label carriers and affixing same to bottles or the like.
- 25 51. A bottle or like labeling machine including rotatable labeling devices which include label carriers rotatable on a horizontal axis, a label box, means for moving said rotatable label carrier to and from said label box in a straight line to pick labels therefrom, said labeling devices including means for stripping the labels from the label carriers and affixing same to bottles or the like.
- 30 52. A bottle or like labeling machine including a label box, labeling mechanism including label carriers rotatable on a horizontal axis, means coacting with said rotatable label carriers for moving the same to and from the label box in a vertical line to pick labels therefrom, said labeling mechanism
- 35 53. A bottle or like labeling machine including a label box, labeling mechanism including label carriers rotatable on a horizontal axis, means coacting with said rotatable label carriers for moving same to and from the label box in a straight line to pick labels therefrom, said labeling mechanism also including means for stripping the labels from the label carriers and affixing same to bottles or the like.
- 40 54. A bottle or like labeling machine including a label box, labeling mechanism including label carriers rotatable on a horizontal axis, means for coacting with said rotatable label carriers for moving the same to and from said label box in a vertical line to pick labels therefrom, said labeling mechanism also including means for stripping the labels from the label carriers and affixing the same to bottles and the like.
- 45 55. A bottle or like labeling machine including a label box, labeling mechanism including label carriers rotatable on a horizontal axis, means coacting with said rotatable label carriers for moving the same to and from said label box in a straight line to pick labels therefrom, said labeling mechanism also including means for stripping the labels from the label carriers and affixing the same to bottles and the like.
- 50 56. A bottle or like labeling machine including a label box, labeling mechanism including label carriers rotatable on a horizontal axis, means for changing the rotary movement of said label carriers to a vertical reciprocating movement to pick labels from said label box, said labeling mechanism also including means for stripping the labels from said label carriers and affixing same to bottles or the like.
- 55 57. A bottle or like labeling machine including a label box, labeling mechanism including label carriers rotatable on a horizontal axis, means for changing the rotary movement of said label carriers to a straight reciprocating movement to pick labels from said label box, said labeling mechanism also including means for stripping the labels from said label carriers and affixing same to bottles or the like.
- 60 58. A bottle or like labeling machine including a label box, labeling mechanism including label carriers rotatable on a horizontal axis, means for changing the rotary movement of said label carriers into a straight reciprocating movement to pick labels from the label box and means for moving the label box out of the path of movement of said label carriers, said labeling mechanism also including means for stripping the labels from the label carriers and affixing same to bottles or the like.
- 65 59. A bottle or like labeling machine including a label box, labeling mechanism including label carriers rotatable on a horizontal axis, means coacting with said rotatable label carriers for moving the same to and from the label box in a vertical line to pick labels therefrom, said labeling mechanism

59. A bottle or like labeling machine, including means for holding labels, rotatable label carriers, means for changing the rotary movement of said label carriers to a straight line movement to pick labels from said label holding means, means for stripping the labels from the label carriers and affixing same to bottles or the like, and means for increasing the speed of said rotary label carriers while the same are being stripped of their labels.
60. A bottle or like labeling machine including a label box, rotary label carriers for picking labels therefrom, means for stripping the labels from the label carriers and affixing same to bottles or the like, and means for increasing the speed of said label carriers while the same are being stripped of their labels.
61. A bottle or like labeling machine including a label box, label carriers rotatable on a horizontal axis for picking labels from said label box, means for stripping the labels from the label carriers and affixing same to bottles or the like and means for increasing the speed of the label carriers while the same are being stripped of their labels.
62. A bottle or like labeling machine including means for holding labels, label carriers rotatable on a horizontal axis, means for moving said rotatable label holding means in a vertical line to pick labels therefrom, means for stripping the labels from the label carriers and affixing same to bottles and the like and means for increasing the speed of the label carriers while their labels are being stripped therefrom.
63. A bottle or like labeling machine including means for holding labels, label carriers rotatable on a horizontal axis, means for moving said rotatable label carriers to and from said label holding means in a straight line to pick labels therefrom, means for stripping the labels from the label carriers and affixing same to bottles and the like and means for increasing the speed of the label carriers while their labels are being stripped therefrom.
64. A bottle or like labeling machine including a label box, rotatable label carriers, means for moving the rotatable label carriers in the direction of the label box in a straight line to pick labels therefrom and to move the rotatable label carriers with labels thereon away from the label box in a straight line, means for stripping the labels from the label carriers and affixing same to bottles or the like, and means for increasing the speed of the label carriers while their labels are being stripped therefrom.
65. A bottle or like labeling machine, including a label box, rotatable label carriers, means for moving said rotatable label carriers to and from said label box in a vertical

line to pick labels therefrom, means for stripping the labels from the label carriers and affixing same to bottles or the like and means for increasing the speed of the label carriers while their labels are being stripped therefrom.

66. A bottle or like labeling machine, including a label box, rotatable label carriers, means for moving said rotatable label carriers to and from said label box in a straight line to pick labels therefrom, means for stripping the labels from the label carriers and affixing same to bottles or the like and means for increasing the speed of the label carriers while their labels are being stripped therefrom.

67. A bottle or other labeling machine including a label box, rotatable label carriers means coacting therewith for moving the same to and from said label box in vertical line to pick labels therefrom, means for stripping the labels from the label carriers and affixing same to bottles or the like and means for increasing the speed of the label carriers while their labels are being stripped therefrom.

68. A bottle or other labeling machine including a label box, rotatable label carriers, means coacting therewith for moving the same to and from said label box in a straight line to pick labels therefrom, means for stripping the labels from the label carriers and affixing same to bottles or the like and means for increasing the speed of the label carriers while their labels are being stripped therefrom.

69. A bottle or like labeling machine including a label box, rotatable label carriers, means for changing the rotary movement of said label carriers into a vertical reciprocating movement to pick labels from said label box, means for stripping the labels from the label carriers and affixing same to bottles or the like, and means for increasing the speed of the label carriers while their labels are being stripped therefrom.

70. A bottle or like labeling machine including a label box, rotatable label carriers, means for changing the rotary movement of said label carriers into a straight reciprocating movement to pick labels from said label box, means for stripping the labels from the label carriers and affixing same to bottles or the like, and means for increasing the speed of the label carriers while their labels are being stripped therefrom.

71. A bottle or like labeling machine including a label box, rotatable label carriers, means for changing the rotary movement of said label carriers into straight reciprocating movement to pick labels from the label box, means for moving the label box out of the path of movement of the label carriers, means for stripping the labels from the label carriers and affixing same to bot-

ties or the like and means for increasing the speed of the label carriers while their labels are being stripped therefrom.

72. A bottle or like labeling machine including a label box, label carriers rotatable on a horizontal axis, means for moving the rotatable label carriers in the direction of the label box in a straight line to pick labels therefrom and to move the rotatable label carriers with labels thereon away from the label box in a straight line, means for stripping the labels from the label carriers, and affixing same to bottles or the like, and means for increasing the speed of the label carriers while the labels are being stripped therefrom.

73. A bottle or like labeling machine including a label box, label carriers rotatable on a horizontal axis, means for moving said rotatable label carriers to and from said label box in a vertical line to pick labels therefrom, means for stripping the labels from the label carriers and affixing same to bottles or the like, and means for increasing the speed of the label carriers while their labels are being stripped therefrom.

74. A bottle or like labeling machine including a label box, label carriers rotatable on a horizontal axis, means for moving said rotatable label carriers to and from said label box in a straight line to pick labels therefrom, means for stripping the labels from the label carriers and affixing same to bottles or the like, and means for increasing the speed of the label carriers while their labels are being stripped therefrom.

75. A bottle or like labeling machine including a label box, label carriers rotatable on a horizontal axis, means coacting with said rotatable label carriers for moving the same to and from the label box in a vertical line to pick labels therefrom, means for stripping the labels from the label carriers and affixing same to bottles or the like, and means for increasing the speed of the label carriers while their labels are being stripped therefrom.

76. A bottle or like labeling machine including a label box, label carriers rotatable on a horizontal axis, means coacting with said rotatable label carriers for moving the same to and from the label box in a straight line to pick labels therefrom, means for stripping the labels from the label carriers and affixing same to bottles or the like, and means for increasing the speed of the label carriers while their labels are being stripped therefrom.

77. A bottle or like labeling machine including a label box, label carriers rotatable on a horizontal axis, means for changing the rotary movement of said label carriers to a vertical reciprocating movement to pick labels from said label box, means for stripping the labels from the label carriers and

affixing same to bottles or the like and means for increasing the speed of said label carriers while their labels are being stripped therefrom.

78. A bottle or like labeling machine including a label box, label carriers rotatable on a horizontal axis, means for changing the rotary movement of said label carriers to a straight reciprocating movement to pick labels from said label box, means for stripping the labels from the label carriers and affixing same to bottles or the like and means for increasing the speed of said label carriers while their labels are being stripped therefrom.

79. A bottle or like labeling machine including a label box, label carriers rotatable on a horizontal axis, means for changing the rotary movement of said label carriers into a straight reciprocating movement to pick labels from the label box, means for stripping the labels from the label carriers and affixing same to bottles and the like, and means for increasing the speed of the label carriers while their labels are being picked therefrom.

80. A bottle or like labeling machine including a member rotatable on a horizontal axis, a pair of label carriers normally rotatable with said member, each label carrier being partially revoluble with relation to each other, means pivoted on said rotatable member for mounting said label carriers, means for connecting said pivoted mounting members, means for swinging one of said pivoted members in the direction opposite to the direction of rotation of said rotatable member to stop the rotation of the label carrier carried thereby, and to impart movement thereto in a straight line to the label.

81. A bottle or like labeling machine including a label box and labeling mechanism, said labeling mechanism including the following devices, a member rotatable on a horizontal axis, a pair of label carriers normally rotatable with said rotatable member, means for pivoting each of said carriers on said rotatable member, each label carrier being movable with respect to its pivoting member, means for connecting the pivoting members of each label carrier together, means for swinging one of the pivoted members and its label carrier on its pivot to stop the rotation of the label carrier and to impart a movement thereto in a radial line in the direction of the label box to engage and pick a label therefrom, the said connection between the two pivoted members communicating the swing of the one member to the other pivoted member to swing said other pivoted member on its pivot in the direction of rotation of the said rotatable member to increase the speed of its label carrier, means for carrying a bottle or

the like to be labeled toward the last mentioned label carrier and means for stripping a label from the last mentioned label carrier while the said last mentioned label carrier is 5 being swung by the pivoted member.

82. A bottle or like labeling machine including a label box, paste supplying means, rotatable labeling mechanism which includes a member rotatable on a horizontal 10 axis, a pair of label carriers, a pivoting member for pivotally connecting each label carrier to said rotatable member, means for swinging one of said pivoting members and its label carrier on said rotatable member to 15 stop rotation of its label carrier and move the same in a radial direction to pick a label from the label box, means for connecting the two pivoting members together to communicate the swing of the one member to the 20 other member to swing the other member in the direction of rotation of the rotatable member to increase the speed of its label carrier in the direction of rotation of the pivoting member and means for stripping a 25 label from the last mentioned carrier during the swing of the said label carrier.

83. A bottle or like labeling machine including a label box, a paste supporting means, a member rotatable on a horizontal 30 axis, a pair of label carriers movably mounted on said rotatable member, means for stopping the rotation of one label carrier and moving the same in a radial direction to pick a label from the label box, and means 35 for simultaneously swinging the other label carrier in the direction of rotation of the rotatable member to increase its speed in the direction of rotation of said rotatable member, means rotatable on a horizontal axis for 40 carrying a bottle or the like and means rotatable therewith for stripping a label from the last mentioned label carrier during the said swing of the last mentioned label carrier.

45 84. A bottle or like labeling machine including a label box, a paste supplying means, a pair of label carriers rotatable on a horizontal axis, means for moving one of said label carriers in a radial direction to pick 50 a label from the label box, means for increasing the speed of rotation of the other label carrier in the direction of rotation thereof and means for picking a label during the said increase of speed of the label carrier.

55 85. A bottle or like labeling machine including a label box, paste supplying means, a plurality of label carriers rotatable on a horizontal axis, means for moving the label carriers successively in a radial direction to pick labels from the label box, means for increasing the rotating speed of the label carriers successively and means for stripping the labels from the label carriers successively and applying same to bottles.

86. A bottle or like labeling machine, a label box, paste supplying means, a plurality of label carriers rotatable on a horizontal axis, means for moving the label carriers successively in a radial direction to 70 pick labels from the label box to carry same to bottles or the like to be labeled, means for stripping the labels from the label carriers and affixing same to bottles or the like, and means for increasing the speed of the label carriers with relation to the label stripping means, while the labels are being stripped from the label carriers. 75

87. A bottle or like labeling machine including a label box, paste supplying means, 80 a plurality of label carriers rotatable on a horizontal axis, means for moving the label carriers successively in a straight line to the label box to pick labels therefrom and carry the same to bottles or the like to be labeled, 85 and means for stripping the labels from the label carriers and applying same to bottles or the like.

88. A bottle or like labeling machine including a label box, means for supplying 90 paste, a plurality of label carriers rotatable on a horizontal axis, means for moving said label carrier in a straight line to the label box to pick labels therefrom and carry same to bottles or the like to be labeled, a plurality 95 of bottle carriers rotatable on a horizontal axis, a plurality of label stripping fingers rotatably mounted on the same horizontal axis with said bottle or like carriers, but stationary relative thereto, said bottle or 100 like carriers and said fingers being rotatable in a direction opposite to that of said label carriers, said rotatable fingers, during their rotation, meeting said label carriers to strip the labels therefrom, means for moving said 105 bottle or like carriers into engagement with the labels on said fingers from said label carriers to receive the labels therefrom, means for increasing the rotating speed of said label carriers with relation to said rotating 110 fingers during the stripping of the labels, and means for wiping the labels on the bottles or the like.

89. A bottle or like labeling machine including a label box, paste supporting means, suitable label carriers rotatable on a horizontal axis to pick labels from the label box and carry the same to bottles or the like, bottle carriers and label stripping fingers rotatable on a horizontal axis, said bottle carriers being movable with respect to the said fingers, the said fingers being stationary with respect to the said bottle carriers, said fingers during their rotation meeting said label carriers to strip the labels therefrom, and means for moving said bottle or like carriers with bottles therein into engagement with the labels on the said fingers. 120 125

90. A bottle or like labeling machine including a label box, a label carrier rotatable 130

on a horizontal axis, means for normally holding said label carrier in a position tangential to its axis of rotation, means for stopping the rotation of said label carrier and moving the same while in a tangential position in a straight line to the label box to pick a label therefrom, means for turning said label carrier out of a tangential position to carry its label into position for being stripped therefrom, means for stripping the label from the label carrier, and means for moving the label carrier in the direction of its rotation to increase the speed thereof while its label is being stripped therefrom.

91. A bottle or like labeling machine including a label box, a label carrier rotatably mounted on a horizontal axis, means for stopping the rotation of the label carrier and for moving the same in a straight line to the label box to pick a label therefrom, means for holding the label carrier normally in a tangential position with respect to its rotating axis, means for moving the label carrier with label thereon out of its normal tangential position and turning the same into position to have its label stripped therefrom, and means for stripping the label from the label carrier and affixing same to a bottle or the like.

92. A bottle or like labeling machine including a label box, a label carrier rotatably mounted on a horizontal axis, means for stopping the rotation of the label carrier and for moving the same in a straight line to the label box to pick a label therefrom, means for stripping a label from said label carrier and affixing same to a bottle or the like, means for moving said label carrier with label thereon into position to meet the rotatable label stripping means, and means for imparting a further movement to the label carrier in the direction of its rotation during the interval that its label is being stripped therefrom.

93. A bottle or like labeling machine including a label box, a label carrier rotatably mounted on a horizontal axis, means for stopping the rotation of the label carrier and for moving the same in a straight line to the label box to pick a label therefrom, means for stripping a label from said label carrier and affixing same to a bottle or the like, means for moving said label carrier with label thereon into position to meet the rotatable label stripping means.

94. A bottle or like labeling machine including a label box, a label carrier rotatably mounted, means for stopping the rotation of the label carrier and for moving the same in a straight line to the label box to pick a label therefrom, means for stripping a label from said label carrier and affixing same to a bottle or the like, means for moving said label carrier with label thereon into position

to meet the rotatable label stripping means, and means for imparting a further movement to the label carrier in the direction of its rotation during the interval that its label is being stripped therefrom.

95. A bottle or like labeling machine including a label box, a label carrier rotatably mounted, means for stopping the rotation of the label carrier and for moving the same in a straight line to the label box to pick a label therefrom, means for stripping a label from said label carrier, means for moving said label carrier with label thereon into position to meet the rotatable label stripping means.

96. A bottle or like labeling machine including a label box, a rotatable member, a pair of label carriers normally rotatable with said member, each label carrier being partially revoluble with relation to each other, means pivoted on said rotatable member for mounting said label carriers, means for connecting said pivoted mounting members, means for swinging one of said pivoted members in the direction opposite to the direction of rotation of said rotatable member to stop the rotation of the label carrier carried thereby, and to impart movement thereto in a straight line to the label.

97. A bottle or like labeling machine including a label box and labeling mechanism, said labeling mechanism including the following devices, a rotatable member, a pair of label carriers normally rotatable with said rotatable member, means for pivoting each of said carriers on said rotatable member, each label carrier being movable with respect to its pivoting member, means for connecting the pivoting member of each label carrier together, means for swinging one of the pivoted members and its label carriers on its pivot to stop the rotation of the label carrier and to impart a movement thereto in a radial line in the direction of the label box to engage and pick a label therefrom, the said connection between the two pivoted members communicating the swing of the one member to the other pivoted member to swing said other pivoted member on its pivot in the direction of rotation of the said rotatable member to increase the speed of its label carrier, means for carrying a bottle or the like to be labeled toward the last mentioned label carrier and means for stripping a label from the last mentioned label carrier and affixing it to the bottle or the like carried thereto while the said last mentioned label carrier is being swung by pivoted member.

98. A bottle or like labeling machine including a label box, paste supplying means, rotatable labeling mechanism which includes a rotatable member, a pair of label carriers, a pivoting member for pivotally connecting each label carrier to said rota-

table member, means for swinging one of said pivoting members and its label carrier on said rotatable member to stop rotation of its label carrier and move the same in a radial direction to pick a label from the label box, means for connecting the two pivoting members together to communicate the swing of the one member to the other member to swing the other member in the direction of rotation of the rotatable member to increase the speed of its label carrier in the direction of the pivoting member and means for stripping a label from the last mentioned carrier during the swing of the said label carrier.

15 99. A bottle or like labeling machine including a label box, a paste supplying means, a rotatable member, a pair of label carriers movably mounted on said rotatable member, means for stopping the rotation of one label carrier and moving the same in a radial direction to pick a label from the label box, and means for simultaneously swinging the other label carrier in the direction of rotation of the rotatable member to increase its speed in the direction of rotation of said rotatable member, rotatable means for carrying a bottle or the like and means rotatable therewith for stripping a label from the last mentioned label carrier during the said

30 swing of the last mentioned label carrier.

100. A bottle or like labeling machine including a label box, a paste supplying means, a rotatable member for moving one of said label carriers in a radial direction to pick a label from the label box, means for increasing the speed of rotation of the other label carrier in the direction of rotation thereof and means for picking a label during the said increase of speed of the label carrier.

40 101. A bottle or like labeling machine including a label box, paste supplying means, a plurality of rotatable label carriers, means for moving the label carriers successively in a radial direction to pick labels from the label box, means for increasing the rotary speed of the label carriers successively and means for stripping the labels from the label carriers successively and applying same to bottles.

50 102. A bottle or like labeling machine, a label box, paste supplying means, a plurality of rotatable label carriers, means for moving the label carriers successively in a radial direction to pick labels from the label box to carry same to bottles or the like to be labeled, means for stripping the labels from the label carriers and affixing same to bottles or the like, and means for increasing the speed of the label carriers with relation to the label stripping means, while the labels are being stripped from the label carriers.

103. A bottle or like labeling machine including a label box, paste supplying means, a plurality of rotatable label carriers, means for moving the label carriers successively in

a straight line to the label box to pick labels therefrom and carry the same to bottles or the like to be labeled, and means for stripping the labels from the label carriers and applying same to bottles or the like.

104. A bottle or like labeling machine including a label box, means for supplying paste, a plurality of rotatable label carriers, means for moving said label carriers in a straight line to the label box to pick labels therefrom and carry same to bottles or the like to be labeled, a plurality of rotatable bottle carriers, a plurality of label stripping fingers rotatably mounted on the same axis with said bottle or like carriers, but stationary relative thereto, said bottle or like carriers and said fingers being rotatable in a direction opposite to that of said label carriers, said rotatable fingers, during their rotation, meeting said label carriers to strip the labels therefrom, means for moving said bottle or like carriers into engagement with the labels on said fingers stripped from said label carriers to receive the labels therefrom, means for increasing the rotating speed of said label carriers with relation to said rotating fingers during the stripping of the labels, and means for wiping the labels on the bottles or the like.

105. A bottle or like labeling machine including a label box, paste supplying means, suitable rotatable label carriers to pick labels from the label box and carry the same to bottles or the like, rotatable bottle carriers and label stripping and affixing fingers, said bottle carriers being movable with respect to the said fingers, the said fingers being stationary with respect to the said bottle carriers, said fingers during their rotation meeting said label carriers to strip the labels therefrom, and means for moving said bottle or like carriers with bottles or the like therein into engagement with the labels on the said fingers.

106. A bottle or like labeling machine including a label box, a rotatable label carrier, means for normally holding said label carrier in a position tangential to its axis of rotation, means for stopping the rotation of said label carrier and moving the same while in a tangential position in a straight line to the label box to pick a label therefrom, means for turning said label carrier out of a tangential position to carry its label into position for being stripped therefrom, means for stripping the label from the label carrier and affixing same to a bottle or the like, and means for moving the label carrier in the direction of its rotation to increase the speed thereof while its label is being stripped therefrom.

107. A bottle or like labeling machine including a label box, a rotatably mounted label carrier, means for normally holding said label carrier in a position tangential to

- to its axis of rotation, means for stopping the rotation of said label carrier and moving the same while in a tangential position in a straight line to the label box to pick 5 a label therefrom, means for turning said label carrier out of a tangential position to carry its label into position for being stripped therefrom, means for stripping the label from the label carrier and affixing 10 same to a bottle or the like, and means for moving the label carrier in the direction of its rotation to increase the speed thereof while its label is being stripped therefrom.
108. A bottle or like labeling machine including a member rotatable on a horizontal axis, a pair of label carriers normally rotatable with said member, each label carrier being partially revoluble with relation to each other, means pivoted on said rotatable 15 member for mounting said label carriers, means for connecting said pivoted mounting members, means for swinging one of said pivoted members in the direction opposite to the direction of rotation of said rotatable 20 member to stop the rotation of the label carrier carried thereby, and to impart movement thereto in a straight line to the label box to pick a label therefrom, the said means for connecting the two pivoted members 25 communicating said swinging movement to the other of the pivoted members to swing the same on its pivot in the direction of rotation of the said rotatable member to increase the speed of the label carrier 30 mounted thereon, and means for stripping a label from the last mentioned label carrier 35

109. A bottle or like labeling machine including a label box, a rotatable member, a pair of label carriers normally rotatable with said member, each label carrier being partially revoluble with relation to each other, means pivoted on said rotatable member for mounting said label carriers, means for connecting said pivoted mounting members, means for swinging one of said pivoted members in the direction opposite to the direction of rotation of said rotatable member to stop the rotation of the label carrier carried thereby, and to impart movement thereto in a straight line to the label box to pick a label therefrom, the said means for connecting the two pivoted members communicating said swinging movement to the other of the pivoted members to swing the same on its pivot in the direction of rotation of the said rotatable member to increase the speed of the label carrier mounted thereon, and means for stripping a label from the last mentioned label carrier during the said swing of its pivoted mounted member and affixing the label so stripped to a bottle or the like.
